UNITED STATES PATENT OFFICE

GEORGE C. SOULE AND JOHN B. WOODBURY, OF SOUTH PORTLAND, MAINE, ASSIGNEES
TO MAINE STEEL PRODUCTS COMPANY, OF PORTLAND, MAINE, A CORPORATION OF
MAINE

SNOWPLOW

Application filed September 29, 1930. Serial No. 485,257.

In the conversion or adaptation of vehicles such as motor driven trucks for special uses, as for the propulsion of snow plow equipment and the like, it is usually necessary to provide an extension for the frame by which connection to the equipment can be made. In snow plow equipment this presents a considerable problem as the trucks for example, available for the work are of different makes and types, differing from each other in important dimensions. The snow plow equipment which they are to propel is also varied and as snow plowing is seasonal work it is important that the equipment be quickly assembled and disassembled. Where a fleet of municipally owned trucks is used for snow work they are apt to be kept on other work until the last moment and then equipped in haste to meet the first snow. For the same reasons the trucks will be called for in the spring and must be released for other work with as little delay as possible.

While the assembly must be done rapidly it must be done accurately as for example where a snow plow nose is to be mounted on a truck. For such work, frame extensions or push beams must be rigid and make connection with the plow nose at predetermined points. Such a plow nose must have proper degrees of clearance from the road and as trucks vary considerably in the height of frame it is necessary that the push beams be made to compensate for such differences.

Our invention therefore contemplates a system of clamping or mounting push beams or the like on the frames of trucks or other motive equipment so as not only to compensate for differences in height, but also differences in the size of frames both as to depth and width.

These and various other features which will be later discussed are shown in an illustrative embodiment present in the accompanying drawings. The snow plow equipment is selected for illustration because it is characteristic and because it represents a field of important development made necessary by modern systems of communication. In the drawings:

Fig. 1 is a side elevation of the clamp shown

on a fragmentary portion of a truck frame, a sectional view of the snow plow being shown in connection therewith.

Fig. 2 is a side elevation of the clamps and the push beam shown in horizontal position. 55

Fig. 3 is the same as Fig. 2, except that the push beam is shown tilted.

Fig. 4 is a sectional plan of the clamp taken on the line 4-4, Fig. 6.

Fig. 5 is a perspective view of the clamp shown mounted on a truck frame.

Fig. 6 is a sectional elevation of the clamp in connection with both the push beam and the truck frame.

Fig. 7 is a side elevation of the main portion of the clamp. 65

Fig. 8 is a section on the line 8-8, Fig. 6, illustrating the space between the clamping parts to allow the push beam to tilt in either direction, and 70

Fig. 9 is a view of the nut used in connection with the push beam clamping bolts.

We have indicated at 1 the forward end of a truck frame beam of any general construction. The plow or plow nose 2 which is slotted at 3 to receive the push rod 4 may be of any construction but in general is adapted to be carried by and propelled by the truck of which the frame 1 is a part. 75

In equipping trucks of different makes we provide the extension piece or channel member 5 which we term a push beam or push arm, one of which is provided for each side of the truck frame. This push beam or push arm 5 has to be variously adjusted for trucks of different make which vary in height and for plows or plow noses which may be of varying types. 80

In order to provide for the desired elevation of the push rod 4 so as to push it normally as to the plow 2, the push beam or push arm 5 is clamped to the frame by a pair of generally similar frame clamp members. The clamp is made up of a main frame clamping member 6 provided with ears 7 adapted to bear on top of the truck frame 1 and a clamping plate 17. The main member 6 is formed on its inner face as a frame contacting surface and is clamped to the truck frame 1 by bolts 8 which pass through the plate 17. The 100

bolt heads are let into channels 9 formed on one of the inner faces of the main member 6 so that the bolts 8 are held against rotation when the nuts 10 are tightened up. The member 6 is provided on its outer face with an external portion 6¹ corrugated as at 6^a to provide a serrated way and said member 6 is adapted to cooperate with a beam or arm clamping member 11 which is similarly corrugated on its inner face to provide a corresponding serrated way coactive with said first named way. The outer face of the arm clamp 11 is formed as an arm contacting surface which bears against the inner side of the push beam 5.

Cooperating with this clamp 11 is an oppositely channelled push beam or push arm clamping member 12 which enters the channel of the push arm or push beam 5 and is bolted securely thereto by bolts 13 the heads 14 of which are held against rotation in slideable cradles 15 which are guided during adjustment in a slot 16 in the member 6. In this way the push arm or push beam clamp members 11 and 12 are adjustable vertically so as to position the end of the push arm or beam 5 either up or down to secure the desired tilt necessary to bring the push rod 4 in the proper position relative to the plow nose 2. The member 11 is provided with flange receiving bosses 11¹ and the member 12 with oppositely faced corresponding bosses 12¹. These, as shown in Fig. 8 are rounded on their flange receiving faces so as to permit the tilt of the push arm or beam 5 relative to the frame member 1 of the truck. In this way the push arm or beam 5 may be firmly clamped while adjusted at any desired angle.

The frame clamping member 6 is clamped to the truck frame 1 by the bolts 8 which pass through the plate 17. This plate is provided with a series of holes 17¹ corresponding to the holes 6^b so that the bolts 8 may be spaced at suitable distance apart to receive various depths of truck frame members.

Referring to Fig. 6 which is a vertical section, and Fig. 4 which is a transverse section, it will be seen that the bolts 8 are first positioned in the apparatus by passing them through the partly hexagonal holes or openings 6^b and the main portion of the frame clamp 6 secured to the truck frame by the bolts 8. Then the bolts 14 after slipping on the collars 15 are singly passed through the large rectangular space 16¹ the lower one being first worked into its position and the upper one following in like manner.

Various modifications in the construction and assembly of the device may be resorted to if within the limits of the appended claims.

What we therefore claim and desire to secure by Letters Patent is:—

1. In a snow plow rig for trucks or the like, a pair of push arms adapted to contact a plow nose beyond the end of the truck

frame, a pair of frame clamp members for each arm, means for adjustably clamping said frame clamp members to frames of different depth and thickness, a pair of coacting arm clamp members, means for adjustably clamping an arm between said arm clamp members in different positions relative to the frame clamp members.

2. In a snow plow rig for trucks or the like, a pair of channelled push arms adapted to contact a plow nose beyond the end of the truck frame, a pair of frame clamp members for each arm, means for adjustably clamping said frame clamp members to frames of different depth and thickness, a pair of coacting arm clamp members having rounded flange bearings permissive of tilt of the arm, means for adjustably clamping an arm between said arm clamp members in different positions relative to the frame clamp members.

3. A clamp for attaching extension arms to the frames of trucks or the like including a pair of coacting frame clamp members, means for adjustably clamping said frame clamp members to frames of different depth and thickness, a pair of coacting arm clamp members, and means for adjustably clamping an arm between said arm clamp members in different positions relative to the frame clamp members.

4. A reversible adjustable clamp for attaching extension arms to the channelled frames of trucks or the like, including a pair of coacting frame clamp members, one of said clamp members having a shoulder adapted to bear on either the upper or lower flange of the frame channel, means for adjustably clamping said frame clamp members to frames of different depth and thickness, a pair of coacting arm clamp members, and means for adjustably clamping an arm between said arm clamp members in different positions relative to the frame clamp members.

5. In a truck converting rig for snow plows or the like, a clamp comprising a hollow block having a frame contacting surface on one face and a way on its opposite face, a pair of coacting clamping plates adapted to embrace an extension push arm, one of said plates adjustably contacting with the block face way, and means for clamping the coacting plates together and to the way.

6. In a truck converting rig for snow plows or the like, a clamp comprising a hollow block having a frame contacting surface on one face and a way on its opposite face, a pair of coacting clamping plates adapted to embrace an extension push arm, one of said plates adjustably contacting with the block face way, and means for clamping the coacting plates together and to the way, said clamping means including bolts having their heads disposed within the hollow block and

held against turning therein, said block having its wall slotted along said way to permit the bolts to be slidably adjustably along it.

7. In a truck converting rig for snow plows or the like, a clamp comprising a hollow block having a frame contacting surface on one face and a serrated way on its opposite face, a pair of coacting clamping plates adapted to embrace an extension push arm, one of said plates having serrations engageable with those on the block face way, and means for clamping the coacting plates together and to the way.

8. In a truck converting rig for snow plows or the like, a clamp comprising a hollow block having a frame contacting surface on one face and a serrated way on its opposite face, a pair of coacting clamping plates adapted to embrace an extension push arm, one of said plates having serrations engageable with those on the block face way, and means for clamping the coacting plates together and to the way said clamping means including bolts having their heads disposed within the hollow block and held against turning therein, said block having its wall slotted along said way to permit the bolts to be slidably adjustable along it.

9. In a truck converting rig for snow plows or the like, a clamp comprising a hollow block having a frame contacting surface on one face and a slotted way on its opposite face, a pair of coacting clamping plates adapted to embrace an extension push arm, one of said plates bearing on the slotted block face way, and clamping means including bolts having their heads disposed within the hollow block and held against turning therein for clamping the coacting plates together and to the way.

10. In a truck converting rig for snow plows or the like, a clamp comprising a hollow block having a frame contacting surface on one face and having a plurality of bolt holes for adjustably clamping to truck frames, and a slotted way on its opposite face, a pair of coacting clamping plates adapted to embrace an extension push arm, one of said plates bearing on the slotted block face way and bolts through the way slot and having their heads disposed within the hollow block and held against turning therein for clamping the coacting plates together and to the way.

55 11. Means for adjustably connecting the channelled frame of a propulsion vehicle to a snow plow nose, comprising a pair of channelled push beams interposed between said frame and nose, said beams being loosely connected to said nose at their forward ends, and means adjustably clamped to said vehicle frame exteriorly thereof at points in rear of their connection with said nose, said clamping means permitting both limited tilting movement of said beams relative to said

frame whereby to accommodate the beams to varying positions of the snow plow nose and limited vertical adjustment of said beams relative to said frame to accommodate the beams to varying depths of frames.

70 12. Means for adjustably connecting the frame of a propulsion vehicle to a snow plow nose, comprising a pair of push beams interposed between said frame and nose, said beams being loosely connected to said nose at their forward ends, and means adjustably clamping said beams to said vehicle frame at points in rear of said connection with said nose, said clamping means including a part disposed towards the outer face of the vehicle frame and a part disposed towards the inner face of a push beam and adjustable vertically with reference to said first named part.

75 13. Means for adjustably connecting the frame of a propulsion vehicle to a snow plow nose, comprising a pair of push beams interposed between said beam and nose and loosely connected at their forward ends to said nose, and clamping means adjustably clamping said push beams to said frame, said clamping means comprising a pair of frame clamp members adapted to be applied to opposite faces of the frame and adjustable thereon to accommodate themselves to frames of different depths and thickness, and a pair of beam clamp members adapted to be applied to opposite faces of a beam, one of said beam clamp members and one of said frame clamp members being formed to permit relative vertical adjustment of the beam clamp members relative to the frame clamp members so that the beams may be adjusted to different angular positions relative to the frame.

80 14. Means for adjustably connecting the frame of a propulsion vehicle to a snow plow nose, comprising a pair of push beams interposed between said beam and nose and loosely connected at their forward ends to said nose, and clamping means adjustably clamping said push beams to said frames at points in rear of said connection of said push beams with said nose, said clamping means comprising a frame clamp member adapted to be applied to one face of the frame, a beam clamp member adapted to be applied to one face of a beam and adjustable vertically relative to said first named part to permit the beam to be adjusted to different angular positions relative to the frame, the opposing faces of said pair of clamping parts being formed to engage with each other throughout their length.

85 15. Means for adjustably connecting the frame of a propulsion vehicle to a snow plow nose, comprising a pair of push beams interposed between said beam and nose and loosely connected at their forward ends to said nose, and clamping means adjustably clampingsaid push beams to said frames at points in
